In Czechoslovakia March 29, 1930

8 Claims. (Cl. 105—115)

This invention relates to an auxiliary engine for steam locomotives. One of the chief aims in the designing of driving engines for railroad vehicles is to reduce as far as possible the weight of the unsprung parts, in order that the traveling engine itself, as well as the super-structure, shall not suffer more than is necessary on traversing the rail joints. For this reason the driving mechanism of locomotives and motor coaches is usually mounted on the framework of the locomotive or on the car frame, both of which are sprung. The transmission to the driving axles is effected by means of any type of movable gearing, e. g. coupling rods or a movably mounted spur wheel, or the like. Designs have also been put into practice in which the driving engine is built as an independent unit, and is mounted oscillatingly with part of its weight on the unsprung driving axle, the remainder of its weight being carried by the sprung framework or car frame (trolley) of the locomotive, so that only a part of the weight of the driving mechanism rests on the axle. The first mentioned type of suspension is usual for locomotives, and particularly for steam locomotives, while the second type is employed mainly in the construction of motor coaches and street cars.

In recent times it has proved increasingly necessary to equip steam locomotives with auxiliary engines which are intended to facilitate the negotiation of steep inclines, and also starting under heavy load. In designing for this purpose the above-mentioned known types of construction have hitherto been employed, the arrangement being such that, apart from the main engine there is also mounted on the framework or trolley of the locomotive, usually between the frame cheeks, a second steam engine the driving power of which is transmitted by means of a movable toothed wheel gear to one of the driving shafts. The second type, that is to say the so-called street-car suspension, is also employed in the mounting of auxiliary engines, but both types of construction are open to serious objections.

It is obvious that the trolley, or the framework, of the locomotive must be more heavily constructed to carry a second driving engine, so that the total weight of the locomotive, and therefore also the load and stress on the super-structure, increase disproportionately. The greatest difficulty, however, is in the accommodation of the auxiliary engine. The most convenient location for the auxiliary engine is the space between the cheeks of the framework which, however, is

already occupied by the necessary bracing. The result has been in practice that in designs employing this method of suspension the engine has been inaccessible, which is a serious disadvantage for the reason that the auxiliary engine is apt to be neglected in the matter of tending, as compared with the remaining parts of the locomotive.

The present invention provides a construction for the auxiliary engine of locomotives in which the described drawbacks are obviated by the provision of the framework of this engine as a closed oil-tight casing which serves at the same time for the rigid connection of the two cheeks of the framework of the locomotive, or of the trolley, and thus replaces the previously necessary bracing. The engine thus constructed requires practically no attention, since it is completely encased and is automatically lubricated, the framework thus constituted being at the same time both simple and very strong. The total weight is considerably reduced, in consequence of the avoidance of the bracing. At the same time the cheeks of the framework may partly or entirely take the place of the side walls of the engine casing, thus enabling a further saving in total weight to be effected.

If the power transmission to the driving axle be effected by means of a toothed wheel gear, which must include movable components in order to permit of the movement of the sprung engine in relation to the axles, it is advantageous to arrange this transmission gear together with the necessary couplings etc. in a separate oil-tight casing, which is independent of the engine casing and movable in relation to the latter. This movement can be provided for in that the gear casing is rotatably and oscillatingly mounted by means of suitable bearings on the driving axle, and is suspended from the framework of the locomotive, or if desired from the casing of the engine, so that it is capable of carrying out an oscillating movement about the axle. The gear casing may comprise a pinion mounted by means of a ball and socket joint upon said axle, and engaging permanently with a gear which is freely mounted upon the non-resiliently mounted axle of the vehicle and may be thrown into and out of engagement with said latter axle by means of a clutch or coupling. In this case it is possible to provide a tight joint, by means of resilient packing, between the movable casing and the fixed casing or the countershaft of the engine, for the purpose of preventing the escape of oil.

In reciprocating steam engines the difficulty

is commonly met with that the oil employed for the lubrication of the pistons, and in certain cases the condensate also, finds its way into the oil case of the engine and contaminates the lubricating oil which has to be changed often. This difficulty can be met by arranging for the cylinders together with their appropriate slide-valve chests to form a special unit, separate from the casing of the engine, this unit being independently connected with the framework of the locomotive or of the trolley, so that there is a clearance between the casing of the engine and the cylinders. The casing is then preferably provided with stuffing boxes for the passage of the piston and slide-valve connecting rods for the purpose of retaining the oil in the casing, and of preventing foreign matter from gaining access to the interior of the casing. A further advantage of the described arrangement of the cylinders, apart from those already cited, is the obviation of strains due to heat in the casing of the engine which can otherwise become very considerable with engines driven by super-heated steam, or in the case of internal combustion engines.

An example of a form of construction in accordance with the present invention is shown in the accompanying drawing illustrating the arrangement of a two-cylinder auxiliary locomotive engine. In the drawing

Fig. 1 represents a plan elevation, in part section, of a portion of a locomotive, showing the auxiliary engine.

Fig. 2 is a horizontal section of the same portion, taken on the line I—I of Fig. 1.

Figs. 3 and 4 show details of the mounting of the crank-shaft and the packing of the casing of the toothed wheel gearing, respectively.

Fig. 5 shows in a top plan view a modification of the construction illustrated in Fig. 1.

Figs. 6 and 7 are detail views of the connection of the pinion 21.

The transmission of power is effected from the cylinders 1 through the piston 6 to the cross-heads 13, and thence by means of the connecting rods 15 to the cranks 16, and further by means of the crankshaft 20, the toothed wheel gearing 21, the coupling 22, and the driving axle 5, to the driving wheels 26 of the locomotive.

The crankshaft drive is enclosed in the oil-tight casing 3 which is attached to the cheeks 2 of the framework of the locomotive, and at the same time constitutes the bracing for the latter. Into this oil-tight casing there are built the bearings 17 for the crankshaft 20, the guides 14 for the crossheads 13, and the bearings 19 for the eccentric shafts; the moving parts, such as the crossheads 13, the cranks 16, and the slide-valve controlling mechanism 18, move within this casing in an oil bath.

In order that the oil in the crank-case may not be contaminated by the condensation water and the oil from the cylinders, the expansion cylinders and the slide-valve chests are separated from this case throughout their entire breadth by the intermediate space 12. The cylinders are cast in a single block 1, and are likewise attached to the cheeks 2 of the framework of the locomotive, thus further contributing to the bracing of this framework. Both the piston rods 6 and the slide-valve rods 9 pass into the casing 3 through the stuffing-boxes 8 and 11.

Parts of the vertical walls 30 of the crank-case are cast in one with the covers of the crank-shaft bearings 17, so that these parts are simul-

taneously removed when the bearing covers are removed, which permits of the convenient opening of the case. The case itself, together with the cheeks 2 of the framework, constitutes a closed well provided with an oil-tight cover 27.

The oil-tight casing 4 in which the spur wheel gearing 21, the couplings 22 with the gear changing device 23, and a portion of the driving shaft 5 are enclosed is movable in relation to the above-described casing 3. The casing 4 is made in two parts and mounted by means of its bearings 28 and 29 on the driving axle 5, and in addition thereto is connected by means of the ball suspension 31 to the casing 3 which is attached to the framework of the locomotive.

The driving axle 5 runs in the bearings 24 which are connected with the framework 2 by means of the springs 25. When these springs are depressed the axle 5 and with it also the case 4 moves in relation to the framework 2. The crank-shaft 20 passes through the openings in the case 4; in order to prevent the escape of oil at these points it is advisable to provide a movable packing 32 which is preferably rigidly connected to the bearings 17, as shown in Fig. 4, since in this manner a reliably tight joint can be obtained.

I claim:—

1. In a locomotive comprising a frame, wheel axles, wheels on said axles, resilient means for supporting said frame on said wheels, and a main steam engine supported by the said frame for propelling the locomotive, the combination of an auxiliary steam engine with frames which are disposed between and rigidly connected to the said first frame to form bracings therefor, one of said frames being constructed to form a casing enclosing the moving parts of the said auxiliary engine.

2. In a locomotive comprising a frame, wheel axles, wheels on said axles, resilient means for supporting said frame on said wheels, and a main steam engine supported by the said frame for propelling the locomotive, the combination of an auxiliary steam engine with frames which are disposed between and rigidly connected to the said first frame to form bracings therefor, one of said frames being constructed to form a casing enclosing the moving parts of the said auxiliary engine, and a tooth wheel transmission driven by the said auxiliary engine and connected to one of said axles to actuate the same.

3. The combination as claimed in claim 2, which includes a chamber enclosing the said tooth wheel transmission, said chamber being supported by the axle actuated by said tooth wheels and the said resilient frame.

4. In the combination of an auxiliary engine with the framework of a steam-driven locomotive, frames for said engine attached to the framework of the locomotive, and adapted to form with their entire structural strength bracings for the said framework, one of said frames being furthermore constructed to constitute a closed oil-tight casing for the moving parts of the said auxiliary engine, the side walls of the said casing being partly formed by the side cheeks of the said framework, and a second independent oil-tight casing for the transmission gear of the said engine, the said second casing being movably connected with the said framework.

5. The combination defined in claim 4, and in which said second casing is mounted on the unsprung driving axle of the locomotive.

6. An arrangement as claimed in claim 1, in

which the side walls of the said casing are partly formed by the side cheeks of the locomotive frame.

7. An arrangement as claimed in claim 1, in which the said walls of the said casing are entirely formed by the side cheeks of the locomotive frame.

8. The combination of an auxiliary engine having cylinders, slide valves, and transmission gear, with the framework of a steam-driven locomotive, an oil-tight casing for the moving parts of

said auxiliary engine constituting a bracing for the locomotive framework, the side cheeks of said framework forming part of said casing, a second independent oil-tight casing for the transmission gear of said engine, and an enclosure for said cylinders and slide valves forming part of said bracing and spaced from the moving parts of the engine.
